UNITED STATES PATENT OFFICE.

HENRY J. WIEGAND, OF MILWAUKEE, WISCONSIN, ASSIGNEE TO THE CUTLER-HAMMER MFG. CO., OF MILWAUKEE, WISCONSIN, A CORPORATION OF WISCONSIN.

ELECTRICAL CONTACT.

1,091,875.

Specification of Letters Patent. Patented Mar. 31, 1914.

Application filed August 3, 1911. Serial No. 643,184.

To all whom it may concern:

Be it known that I, HENRY J. WIEGAND, a citizen of the United States, residing at Milwaukee, in the county of Milwaukee and State of Wisconsin, have invented new and useful Improvements in Electrical Contacts, of which the following is a full, clear, concise, and exact description, reference being had to the accompanying drawing, forming a part of this specification.

My invention relates to improvements in electrical contacts.

It is one of the objects of my invention to provide a contact of simple and inexpensive construction especially adapted for use in devices where plastic compositions are employed for embedding or incasing parts of the device, the contact to be firmly secured in position by the plastic material.

Various other objects and advantages of my invention will be hereinafter clearly and fully set forth.

For the purpose of clearly and fully setting forth the nature and characteristic features of my invention, I shall describe the embodiment thereof illustrated in the accompanying drawing. It should be understood however, that my invention is not limited to the specific form thereof illustrated, but is susceptible of modification and of use in various different relations from that illustrated.

In the accompanying drawing:—Figure 1 shows a side view of a contact button and illustrates one method of mounting the same. Fig. 2 shows a plurality of buttons in top plan similar to the one shown in Fig. 1 arranged on an arc. Figs. 3 and 4 are sectional views on lines 3—3 and 4—4 respectively of the left hand button of Fig. 2.

The contact button illustrated comprises an inverted cup shaped member 1, the closed extremity 2 thereof being flattened to provide a suitable contact surface. The open end of the portion 1 is provided with an angularly disposed annular flange 3 which in practice may be of any desired width. The provision of this flange is a very desirable feature. It forms a substantial seat or base for the contact button and if formed by means of a die insures a uniformity of the buttons thus produced without the necessity of any trimming or special finishing of the edges of the material used. At diametrically opposite points the flange 3 is provid-

ed with downwardly extending lugs or prongs 4 and 5 suitable for securing or at least partially securing the button to a suitable base. Of course in practice these lugs might be of various different forms and provided in any desired numbers and at any desired points on the flange. Also provided at diametrically opposite points on the flange 3 are angular upwardly extending lugs 6 and 7 for facilitating the connection of the button in circuit. In practice the up-turned lugs might of course be of any preferred form and provided in any desired numbers and at any desired points on the periphery of the flange. However, where the contact buttons are to be arranged on an arc as illustrated in Fig. 2, I prefer to form both sets of lugs in close proximity as shown to enable the buttons to be placed in close proximity. With the two sets of lugs in close proximity, it is obvious that the buttons may be placed in very close proximity without interference of the up-turned lugs with the up-turned lugs of adjacent buttons, or with the adjacent buttons themselves, whereas if the two sets of lugs were spaced far apart the buttons would obviously have to be spaced accordingly.

A button of the type illustrated may be formed in a very simple and accurate manner and at a low cost by stamping or punching the same from sheet metal, only a single operation being required to produce the complete device.

Such a button as that illustrated is very desirable and advantageous for use in rheostats where the resistance elements are embedded in a plastic insulating compound, as for example cement. It is this use or application of the contact button that I have shown in Fig. 1 which shows in section a portion of an insulating base 8 with a cement filling 9, embedding a resistance unit 10. The lugs 4 and 5 of the contact button are shown as projecting into recesses provided in the base 8. The engagement of the lugs 4 and 5 with the base 8 in this manner insures retention of the button in the proper position upon the base during and after the application of the cement filling 9. Also these lugs prevent the contact button from turning. The flange 3 rests directly upon the upper surface of the base 8, thereby providing a substantial and firm seat for the button and at the same time provides

a substantial surface against which the cement may be packed to anchor the button in place. The lug 7 to which the resistance 10 is connected also forms an additional 5 means for anchoring the button in place.

It will thus be seen that in this application of the contact button no special fastening means whatever is required. The button is firmly secured in place by its lugs and 10 by the material utilized for embedding the resistance. As above stated, however, the buttons might be used in various other relations than that illustrated.

Having thus described my invention, what 15 I claim as new and desire to obtain by Letters Patent is:

1. A sheet metal contact comprising in cross section a substantially inverted U-shaped member provided at its base on opposite sides thereof with laterally projecting portions.

2. A sheet metal contact of a substantially inverted U-shape in cross section and provided with one or more laterally extending 25 portions for engagement with a suitable base and one or more upwardly extending lugs for electrical connection.

3. A sheet metal contact having a flat base, a contact portion raised from said base 30 and lugs extending downwardly and upwardly from said base, the former for engagement with a suitable support and the latter for electrical connection.

4. A contact comprising a hollow elongated body portion, provided at its base

with an angularly disposed annular flange, and with upwardly and downwardly extending sets of lugs on the periphery of said flange, the lugs of the two sets being formed in close proximity to permit a plurality of 40 contacts to be placed in close proximity.

5. In combination, a base, a sheet metal contact having portions projecting into said base, a plastic composition surrounding said contact and adhering to said base, said contact also having laterally extending portions projecting therefrom into said plastic composition.

6. In combination, a base, a substantially cylindrical sheet metal contact resting on 50 and upon said base, a plastic composition surrounding said contact and adhering to said base, said contact having portions projecting into said plastic composition and into said base.

7. In combination, a base, a plastic body adhering thereto, an elongated contact resting on end upon the surface of said base, all but the upper extremity of said contact being embedded in said plastic body, said contact having portions projecting therefrom into said plastic body and portions projecting into said base.

In witness whereof, I have hereunto subscribed my name in the presence of two witnesses.

HENRY J. WIEGAND.
